(57) CLAIM

The ornamental design for a iron type head for a golf club, substantially as shown.

DESCRIPTION

FIG. 1 is a perspective view showing the rear, top and toe end of an iron type head for a golf club embodying the new design;

FIG. 2 is a rear elevational view thereof;

FIG. 3 is a front elevational view thereof;

FIG. 4 is a top plan view thereof;

FIG. 5 is a bottom plan view thereof;

FIG. 6 is a toe end elevational view thereof;

FIG. 7 is a heel end elevational view thereof;

FIG. 8 is a sectional view taken generally on the line 8—8 of FIG. 2;

FIG. 9 is a perspective view showing the rear, top and toe end sides of an alternative form of the new design, the front, right and left side elevational views and the top plan view being identical to the embodiment of FIGS. 1-8;

FIG. 10 is a rear elevational view the embodiment of FIG. 9, and,

FIG. 11 is a sectional view taken on the line 11—11 of FIG. 10.

The dotted line depiction of a faceplate groove pattern is for illustrative purposes only and forms no part of the claimed design.
